ABSTRACT OF THE DISCLOSURE

In order to warn an operator of an improper operating condition of an internal combustion engine having a pump circulating liquid therethrough during operation of the engine, a visual signal arrangement is provided which normally varies a visual indication in a predetermined manner with changes in operating conditions of the engine, so that a failure of such variation warns the operator that the engine is operating improperly.

In many applications where power from a prime mover is required, the power source of choice is an internal combustion engine. While such engines have significant advantages for such applications, the engines additionally suffer from certain disadvantages. The primary disadvantage is that the engines are subject to incapacitating damage should operation of an engine be attempted or be permitted to continue while the engine is in an improper condition.

While the number of possible improper conditions of an engine is relatively great, many of the conditions are self-incapacitating, and will interrupt operation of the engine or preclude starting operation of the engine. Two particular conditions are, however, not self-incapacitating until major damage has been done to the engine. These conditions result from failure of certain accessory systems included in order to assure operation of the engine. More specifically, most internal combustion engines employed as prime movers are liquid cooled, and include an engine driven pump operative to circulate a liquid through heat exchange passages in the engine and to a heat exchange device, such as a radiator. Regardless of whether or not an engine relies upon a liquid coolant system of this type, the circulation of oil to the lubricated parts of the engine is invariably required in order to assure proper lubrication. Such lubricant systems typically include an engine driven pump circulating lubricant from a reservoir such as a sump in the crankcase of the engine to the various engine parts.

As to both of these liquid circulating systems, it is possible that an improper operating condition may occur without immediate damage to the engine. However, continued operation of the engine will result in critical damage thereto. Thus, it would be preferable that an operator of the engine be warned against any improper operating condition affecting the coolant and lubricant circuits.

With the above discussion in mind, it is an object of my invention to provide apparatus which, in combination with an internal combustion engine having a pump circulating liquid therethrough during operation of the engine, will function to warn an operator of the engine of an improper operating condition. In realizing this object of the invention, I provide apparatus which may be adapted for response either to an improper operating condition in a coolant flow circuit or to an improper operating condition in a lubricant flow circuit. In particular, the apparatus in accordance with my invention includes a visual signal means having an annunciator member movable between extended and retracted positions and operatively connected with a liquid flow circuit of the internal combustion engine in such a manner that fluctuations in pres-

2

sure developed in the circuit during normal operations cause the annunciator member to move between the extended and retracted positions on changes in the operation of the engine which cause significant differences in pressure in the circuit. In view of this normal movement of the annunciator member, a failure of such movement or movement at an abnormal time effectively warns the operator of the engine that the engine is operating improperly.

Some of the objects and advantages of the invention having been stated, others will appear as the description proceeds, when taken in connection with the accompanying drawings, in which—

FIGURE 1 is a schematic illustration of the combination of my invention as arranged to warn an operator of an improper lubricant circuit operating condition;

FIGURE 2 is an elevation view, in section, through a valve means included in the combination of FIGURE 1;

FIGURE 3 is an end elevation view, in section, through a portion of the valve structure of FIGURE 2, taken generally along the line 3—3 in that figure;

FIGURE 4 is an elevation view, in section, through a visual signal means used in the combination of FIGURE 1;

FIGURE 5 is a view similar to FIGURE 1 showing the application of my invention to the coolant flow circuit of an internal combustion engine;

FIGURE 6 is a view similar to FIGURE 4 of the visual signal means included in the combination of FIGURE 5; and

FIGURE 7 is an elevation view in section through a portion of the visual signal means of FIGURE 6, taken generally along the line 7—7 in that figure.

Referring now more particularly to the drawings, the combination of my invention is there illustrated as arranged for warning an operator of an improper operating condition in the lubricant flow circuit of an internal combustion engine (FIGURES 1—4) and as arranged for warning an operator of an improper operating condition in the coolant flow circuit of an internal combustion engine (FIGURES 5—7). The present discussion will proceed first with reference to the combination as arranged for warning an operator of an improper lubricant flow circuit operating condition.

In the combination illustrated in FIGURE 1, it is assumed for purposes of illustration only that the internal combustion engine 10 is employed to provide motive power for a self-propelled vehicle, such as a bus or a truck. While this is a common use of internal combustion engine prime movers and provides an environment for disclosure of the combination of my invention, it is to be understood at the outset that the usefulness of my invention has a wider scope than application only to automotive vehicles. Included in the engine 10 is a lubricant circulating pump 11, typically driven by operative connection with the main shaft of the engine 10, in a conventional manner. The lubricant pump 11 withdraws oil or other suitable lubricant from a reservoir 12 such as the pan portion of the crankcase for the engine 10, and circulates the lubricant to the bearings and other lubricated parts of the engine as is conventionally known.

In order to advise an operator of the engine 10 of an improper lubricant flow circuit condition, the combination of my invention includes a housing generally indicated at 20 and visual signal means supported by the housing in position for ready observation by an operator of the engine 10. In the particular environment illustrated in FIGURE 1, the housing 20 may be mounted in position above the windshield through which the operator of the engine 10 views the road or path of travel of the automotive vehicle driven by the engine 10. The visual signal means includes an annunciator member preferably

in the form of a pivoting flag 21 engaged by an actuating rod 22 and mounted on the housing 20 for movement between extended and retracted positions (as respectively shown by the full line and phantom line positions of FIGURE 4).

In order to assure movement of the pivoting flag 21 in the desired manner, the flag is mounted on the housing 20 for movement relative thereto about a pivot axis determined by a pivot pin 24, and the actuating rod 22 penetrates the housing 20 and is positioned to transmit movement to the pivoting flag 21 at a cam surface 25 by movement of the actuating rod 22 along a line spaced from the pivot axis defined by the pin 24. Preferably, an antifriction member such as a bearing ball 26 is interposed between an end of the actuating rod 22 and the cam surface 25 of the pivoting flag 21, in order to assure low friction engagement of the respective surfaces upon transmission of movement. As the actuating rod 22 is moved to an extended position, under the influence of forces to be discussed more fully hereinafter, the pivoting flag 21 is moved from the extended position (solid lines in FIGURE 4) to the retracted position (phantom lines in FIGURE 4).

In order to transmit to the annunciator member of the visual signal means movement which is indicative of the operating condition of the engine 10, the apparatus of my invention includes a displaceable member mounted within the housing 20 for defining therewith an expandable chamber. Preferably, the displaceable member is a flexible diaphragm membrane 28, clamped in place between an upper housing member 29 and a lower housing member 30 which receives and supports the actuating rod 22 and pivoting flag 21. The diaphragm membrane 28 may be made of any suitable material adaptable to diaphragm construction, such as a plastic film, a rubberized fabric, or similar known materials. By being clamped in place between the upper and lower housing members 29 and 30, the diaphragm membrane 28 provides a flexible wall for an expandable chamber 31 therewithin. The diaphragm membrane 28 is operatively connected to the visual signal means, preferably by having the actuating rod 22 penetrate the central portion of the membrane 28 and be secured with appropriate reinforcing washers on the opposite faces thereof. By this operative connection, movement of the membrane 28 within the housing 20 with expansion and contraction of the volume of the chamber 31 is transmitted to the visual signal means.

In order to normally bias the visual signal means toward one of the selected positions, means are provided for resiliently biasing the diaphragm membrane 28 toward a reduced chamber volume position. Preferably, the resilient biasing means is a compression spring 32, positioned encircling the actuating rod 22 for engagement with the lower housing member 30. Upon movement of the diaphragm membrane 28 toward a position at which the volume of the chamber 31 is enlarged, the spring 32 is compressed and provides a resilient biasing force tending to return the actuating rod 22 to the retracted position and the pivoting flag 21 to the extended position.

In order to permit movement of the pivoting flag 21 in response to fluctuations in pressure developed by the lubricant pump 11 during normal engine operation, the combination of my invention further includes means for normally establishing operative communication between the expandable chamber 31 within the housing 20 and the lubricant pump 11, for normally transmitting to the diaphragm member 28 the pressure developed by the pump 11 in circulating liquid through the engine. In the combination with which the present discussion is concerned, the means for normally establishing operative communication between expandable chamber 31 and the pump 11 includes a conduit 34 (FIGURES 1 and 4) communicating with the expandable chamber 31, a conduit 35 communicating with the discharge side of the lubricant pump

11, and a valve means 36 (FIGURES 1, 2 and 3) interposed between the conduits 34 and 35 for controlling the transmission of pressure therethrough. The valve means 36 is provided in order that the apparatus be responsive to an undesirable lowering of the quantity of lubricant held in the reservoir 12, and includes a float member 38 disposed within the reservoir 12 and movable in response to fluctuations in the level of lubricant therein. Normally, the float 38 is immersed wholly in and buoyed upwardly by the quantity of lubricant retained in the reservoir 12 (in the dotted line position of FIGURE 2).

The float member 38 is mounted on and pivotally movable relative to a valve body 39, with which the conduits 34 and 35 communicate. Operative communication between the conduits 34 and 35 is controlled by a valve member 40 disposed within the valve body 39 and movable relative to a valve seat provided in a valve passage which joins the conduits 34 and 35. The valve body 40 moves in response to movement of the float member 38, between a passage open position removed from the valve seat when the quantity of lubricant retained in the reservoir 12 is sufficient to buoy the float member 38 to the phantom line position in FIGURE 2 and a passage closed position in which the valve member 40 is seated when the quantity of lubricant in the reservoir 12 drops to such a level that the weight of the float member 38 acts on the valve member 40.

In order to release the pivoting flag 21 for movement to the extended position upon seating of the valve member 40, and to thus warn the operator of the engine 10 that the lubricant level has dropped to a critically low point, the valve member 40 has a spool configuration and cooperates in a particular manner with the passages through the valve body 39 (FIGURES 2 and 3). As illustrated, the valve member 40 has a conical seat engaging nose, a main body portion having a diameter less than that of the passageway within which the member moves, and a guiding flange portion adjacent the lower end of the member which sealingly engages the passageway. The length of the valve member 40 and the distance over which it moves in response to movement by the float 38 are correlated in such a manner that the flange portion of the member 40 blocks communication between the conduit 35 connecting the valve 36 to the signal housing 20 during normal engine operation, so that lubricant pump pressure is passed thereto. Upon the level of lubricant falling to an undesirably low condition, the valve member 40 seats to block communication between the conduits 34 and 35, while movement of the flange portion thereof open direct communication between the conduit 35 and the lubricant sump 12 thereby permitting the release of pressure from the housing 20.

The various elements of the combination of my invention now having been described, with reference to a system for indicating an improper lubricant flow circuit operating condition, the operation of the apparatus will now be more fully pointed out. With a normal quantity of lubricant retained in the reservoir 12, the valve body 40 is withdrawn from the valve seat and free communication is established between the expandable chamber 31 within the housing 20 and the discharge side of the lubricant pump 11. With the engine in a non-operating condition, no pressure is present in the conduits 34 and 35 or in the expandable chamber 31 and the pivoting flag 21 is thus moved to the extended position by the retraction of the actuating rod 22 under the influence of the spring 32. Then, upon starting of the engine, the pressure produced by the lubricant pump 11 is applied through the conduits 34 and 35 and the valve means 36 to the expandable chamber 31 and the membrane 28. Overcoming the biasing force of the spring 32, the pressure of the lubricant pushes the diaphragm membrane 28 to the expanded chamber position, extends the actuating rod 22, and moves the pivoting flag 21 to the retracted position. Thus, an operator of the engine should

observe that the visual signal means is in the extended position prior to start-up of the engine, and moves to the retracted position promptly as the engine starts.

With continued operation of the engine, the annunciator member is retained in the retracted position. Should the quantity of lubricant retained in the reservoir 12 be maintained at the proper level throughout the period of operation of the engine 10 and until the engine is stopped, the reduction of pressure in the conduits 34 and 35 coincident to stopping of the lubricant pump 11 will permit the annunciator member to return to the extended position, thereby indicating to the operator of the engine that satisfactory operating conditions persist. In the event that an improper operating condition for the engine occurs, as by the loss of sufficient lubricant from the lubricant flow cycle to permit the float 38 to drop and the valve member 40 to move to the seated position, the pressure retained in the conduit 34 is released, the annunciator moves to the extended position, and the operator is warned of an improper operating condition in the lubricant flow circuit of the engine 10.

While discussed thus far with reference to an apparatus for warning an operator of an improper lubricant flow circuit condition, it is additionally contemplated that the apparatus of my invention may be so arranged as to warn an operator of improper coolant flow through the engine. Such a system is shown in FIGURES 5-7, wherein corresponding portions of the apparatus are identified by the same reference characters used in the combination of FIGURES 1-4, with the addition of prime notation as will become more clear hereinafter. As to the combination which is particularly adapted for warning of an improper coolant flow, the internal combustion engine 10 is there shown in greater detail and in section, in order to illustrate a coolant jacket 41 enclosing a cylinder of the engine, for permitting the flow of a coolant liquid such as water in the area immediately surrounding the cylinder. As is well known, the flow of coolant to such a jacket 41 is induced by an engine driven pump which circulates liquid through the engine 40 and to some heat exchanger such as a radiator.

In order to respond to the pressure developed by the coolant pump, a conduit 42 is provided for establishing operative communication between coolant jacket 41 and an expansible chamber 31' within a housing 20'. By means of the conduit 42, whatever pressure is applied to coolant flowing in the jacket 41 is transmitted to a displaceable diaphragm membrane 28'. As a result, the warning apparatus responds to a decrease in coolant pressure such as results from a rupture in the coolant flow circuit and to a continuance of high coolant pressure such as results when the engine is stopped but gases from the cylinder have escaped into the coolant flow circuit.

More particularly, the operation of the combination for the present invention as illustrated in FIGURES 5-7 is dependent upon normal rise and fall of coolant pressure within the jacket 41 and upon the influence on that pressure of the presence of an improper operating condition. Normally, prior to engine start-up, the pressure applied to the coolant within the jacket 41 is substantially atmospheric and is insufficient to overcome the resilient biasing force applied by the spring 32'. Accordingly, the pivoting flag 21' is positioned in the extended position. On start-up of the engine, the pressure applied to the coolant within the jacket 41 rises, overcoming the biasing force of the spring 32' and raising the pivoting flag 21' to the retracted position. Thereafter, should the coolant flow circuit rupture during operation of the engine, the pressurization normally applied to the coolant within the jacket 41 will drop rapidly, permitting spring 32' to return the diaphragm member 28' to the reduced chamber volume position and causing the pivoting flag 21' to drop to the extended position and warn an operator of the engine. Further, should some engine failure such

as a leaking head gasket permit pressure from one of the operating cylinders of the engine to flow over into the coolant jacket, as is typical with such an occurrence, the pressure within the jacket 41 will not fall upon stopping of the engine 10 and the pivoting flag 21' will not be returned to its normal extended position. In either instance, the attention of an operator will be drawn to the unexpected movement or failure to move of the pivoting flag 21', warning the operator of an improper coolant flow.

In the drawings and specification, there has been set forth preferred embodiments of the invention, and although specific terms are employed, they are used in a generic and descriptive sense only and not for purposes of limitation, the scope of the invention being defined in the claims.

I claim:

1. In an internal combustion engine having a pump circulating a liquid therethrough during operation of the engine, the combination therewith of apparatus for warning of an improper operating condition of the engine and comprising:

a housing, means for normally establishing operative communication between said housing and the pump for normally transmitting to said housing the pressure developed by the pump in circulating liquid through the engine.

means in said housing for movement in response to fluctuations in pressure developed by the pump as transmitted to said housing and including an actuating rod restrained by said housing to linear movement along an axis of reciprocation, and

visual signal means supported by said housing in a position for ready observation by an operator of the engine and including a pivoting flag mounted on said housing for movement about a pivot axis offset from said axis of reciprocation, said pivoting flag having a cam surface thereon extending in predetermined spaced relation to said pivot axis and intersecting said axis of reciprocation, said actuating rod being operatively coupled to said cam surface for movement of said flag between extended and retracted positions indicative of the operating conditions of the engine in response to linear movement of said actuating rod,

so that the fluctuations in pressure developed by the pump during normal engine operation causes the pivoting flag to move between the extended and retracted positions and failure of such movement warns the operator that the engine is operating improperly.

2. The combination of claim 1 particularly adapted for warning an operator of improper coolant flow through the engine and wherein said means establishing communication between the pump and said housing comprises a conduit connected at one end to a coolant jacket enclosing a cylinder of the engine and connected at the other end to said housing for transmitting thereto whatever pressure is applied to coolant flowing in the jacket, so that the warning apparatus responds to a decrease in coolant pressure such as results from a rupture in the coolant flow circuit and to a continuance of high coolant pressure such as results when the engine is stopped but gases from a cylinder have escaped into the coolant flow circuit.

3. The combination of claim 1 wherein said visual signal means is so oriented that said pivoting flag is biased by gravity toward the extended position and is moved by said actuating rod against gravity toward the retracted position.

4. The combination of claim 1 particularly adapted for warning an operator of improper lubricant supply to the engine and wherein said means establishing communication between the pump and said housing com-

prises a conduit connected at one end to an outlet from an engine oil pump and at the other end to said housing for transmitting thereto the pressure applied to oil flowing to the engine and further comprising valve means interposed in said conduit and operable in response to a reduction in the volume of lubricant in a reservoir from which the engine oil pump is drawing lubricant for closing said conduit, so that the warning apparatus responds to a loss of lubricant from the reservoir and to a loss of oil pressure such as may result from a rupture in the lubricant flow circuit.

5. The combination of claim 4 wherein said valve means comprises a float member normally submerged in and buoyed by lubricant in the engine reservoir, a valve passage interposed in said conduit connecting said chamber and the oil pump and including a valve seat, and a valve member movable in said valve passage in response to movement of said float member and for engaging said valve seat and sealing against flow thereby

10

15

upon movement of said float member to a position indicative of excessive loss of lubricant from the reservoir.
